SEAT SPRING STRUCTURE

Jacob L. Alpert, Los Angeles, Calif.

Application October 22, 1946, Serial No. 704,831

6 Claims. (Cl. 155—179)

1

My invention relates to spring structures more particularly adapted, although not necessarily, to be used in seats of chairs, davenport, and other forms of like furniture.

A purpose of my invention is the provision of a seat spring structure which is structurally characterized by its simplicity, low cost of manufacture and durability, and functionally by its high degree of resiliency to produce a superior cushioning action under all human loads, to be stable in its cushioning property to support a sitting person substantially horizontally and without side sway, and to thus prevent injury or rapid wear of those parts of the furniture with which it may be associated.

I will describe only one form of seat spring structure in its adaptation to a chair, and will then point out the novel features thereof in claims.

In the accompanying drawings:

Fig. 1 is a view showing in broken lines the conventional form of upholstered chair, with the seat frame in section, and having applied thereto one form of spring structure embodying my invention.

Fig. 2 is a central vertical longitudinal sectional view of the spring structure and seat frame shown in Fig. 1, as seen on line 2—2 of Fig. 1.

Fig. 3 is a top plan view of the spring structure as mounted on the seat frame, with a portion of the web of the structure broken away to reveal the stabilizing spring elements.

Fig. 4 is an enlarged fragmentary view partly in section, showing the sliding connection between the frame of the spring structure and one of the spring legs.

Fig. 5 is an enlarged sectional view taken on the line 5—5 of Fig. 3.

The seat spring structure of my invention is capable of embodiment in various forms of furniture, upholstered or otherwise. However, in its present embodiment it is incorporated in a conventional upholstered chair shown in broken lines in Fig. 1, and having the usual sides 15, back 16, feet 17, and a side frame T usually made of wood and suitably secured to the sides and back of the chair. This frame is rectangular and is made up of upper side and end rails 18 and 19, and lower side and end rails 20 and 21.

The spring structure, in its present embodiment, comprises a pair of springs S of identical construction, and each made from a single length of relatively heavy wire bent to form a pair of coils 22 that may have one or more convolutions as the case may require. These coils are

interconnected by a linear section 23 which is fixedly secured to one of the lower side rails 20 preferably by a clamping bracket 23a. From the coils 22 the wire is extended tangentially upward to provide a pair of crossed and upwardly extending legs 24 and 25. These legs so extend from the coils that they are in spaced relation one to the other, and, hence, free to move in vertical planes.

10 Above the springs S and supported by the legs 24 and 25 of both of the springs, is a metal frame F of rectangular form likewise constructed of relatively heavy wire and including end portions 26 and side portions 27. The upper ends of the 15 legs 25 are fixedly secured to the front end portion 26 of the frame F at the points indicated at 28, while the upper ends of the legs 24 are curved as indicated at 29 in Fig. 4, and extended through and locked in the lower rounded portions of 20 sleeves 30, the upper portions of such sleeves being slidably mounted on the side portions 27 of the frame F.

Within the frame F a conventional web 31 is held in extended position by a plurality of coiled 25 springs 32, each of which, as shown in Fig. 5, has one terminal hook 33 engaging the sides or end portions 26 or 27 of the frame F, as the case may be, and arranged at spaced intervals along the length of said portions. The inner end of each 30 spring 32 is likewise provided with a hook 34 which engages metal rods 35 extending through sleeves 36 formed on the two side edges and the rear edge of the web 31. The remaining or front edge of the web 31 is formed with a sleeve 36a 35 through which the front end portion 26 of the frame F is extended. These sleeves are formed by folding and stitching the web upon itself, as more clearly illustrated in Fig. 5.

The aforescribed arrangement of springs and 40 rods in relation to the frame F and the web 31, manifestly holds the web in fully extended position within the frame to prevent sagging thereof under the weight of the sitter when reposing on a cushion 37 superimposed on the web, as illustrated in Fig. 1.

Elements E are included in my spring structure 45 for stabilizing both the springs S and the frame F against any lateral sway, so that the springs, frame, and web, under the weight of the sitter, 50 will move vertically and not to either side, thereby utilizing the full resiliency of the springs to obtain maximum cushioning action under all loads, and also to prevent injury or rapid wear of the adjacent parts of the chair, which would 55 result if the spring structure were permitted to move in any plane but a vertical plane.

Two such elements E are, in the present instance, provided, and arranged in intersecting relation transversely of the springs S and preferably, although not necessarily, interconnecting the frame F with the seat frame T. Each element E is made up of a coiled spring 38 having hooked ends 39, one of which is connected to a relatively short wire strand 40 and the other of which is connected to a wire strand 41 which is relatively long. The lower end of the strand 40 is secured to one of the lower side rails 20 by a screw eye 42, while the upper end of the strand 41 is formed with a loop 43 which engages one of the side portions 27 of the frame F.

With the stabilizing elements E so constructed and associated with the seat frame T and the cushion supporting frame F, it will be understood that when properly tensioned, the springs 38 will function to maintain the springs S, more particularly the legs thereof, for movement in vertical planes, and the frame F against any edgewise shifting.

In practice, the weight of any person sitting on the cushion 37, will be imposed on the web 31, but this being held taut by the springs 32 the weight will be transmitted to the frame F to depress the legs 24 and 25 against the tension of the coils 22, the legs 24, sliding on the frame F to allow lowering movement of the frame and web. In consequence, the coils 22 serve to resiliently support the frame F, the web 31, and the cushion 37 to provide a superior cushion action for the sitter. Due to the fact that the legs 24 and 25 are confined to movements in vertical planes by the stabilizing elements E, it becomes manifest that the frame and web will move likewise in a vertical plane to the elimination of any side swaying and to thus support the person substantially horizontally, and to insure the return of the frame and web to elevated position under the action of the springs S when the weight of the person is removed from the cushion.

Although I have herein shown and described only one form of seat spring structure embodying my invention, it is to be understood that various changes and modifications may be made therein without departing from the spirit of my invention and the spirit and scope of the appended claims.

I claim:

1. A seat spring structure adapted to be mounted on a seat frame, comprising: springs coiled in vertical planes and secured to the seat frame, each having upwardly extending and crossed legs; a web supporting frame above said springs; means for fixing the upper end of one leg of each spring to one end of the web supporting frame; and means for connecting the upper end of the other leg of each spring to a side of said frame.

2. A seat spring structure adapted to be mounted on a seat frame, comprising: springs coiled in vertical planes, spaced one from the other and secured to the seat frame, each spring having upwardly extending and cross legs; a web supporting frame above said springs; means for securing the free ends of said legs to the web supporting frame; and stabilizing springs connected to the seat frame and to the web supporting frame and extending transversely of the first mentioned springs.

3. A seat spring structure adapted to be mounted on a seat frame, comprising: a pair of springs coiled in vertical planes, and arranged in spaced

parallelism, each spring including a pair of coils interconnected and secured to the seat frame, and upwardly extending and crossed legs; a supporting frame above said springs; means for fixing the upper end of one leg of each spring to one end of the web supporting frame; and means for slidably connecting the upper end of the other leg of each spring to a side of said frame.

4. A seat spring structure as embodied in claim 10 8, wherein a fabric web is arranged within the web supporting frame, with one edge secured to the latter; rods in the other edges of said web; and springs connected to said frame and to said rods for resiliently holding said web in extended position within said frame.

5. A seat spring structure adapted to be mounted on a seat frame, including: springs coiled in vertical planes and secured to the seat frame, each spring having upwardly extending and crossed legs disposed in different vertical planes; a supporting frame of substantially rectangular outline to the side portions of which the upper end of one leg of each spring is secured, and to one end portion of which the upper end of the other leg of each spring is secured and resiliently supported by said springs; a substantially rectangular web within the supporting frame having sleeves in all of its edges through one of which one end portion of said supporting frame extends; rods in the other sleeves of said web; and coiled springs connected to the side portions and the other end portions of said supporting frame and to said rods.

6. A seat spring structure adapted to be mounted on a seat frame, including: springs coiled in vertical planes and secured to the seat frame, each spring having upwardly extending and crossed legs disposed in different vertical planes; a supporting frame of substantially rectangular outline to the side portions of which the upper end of one leg of each spring is secured, and to one end portion of which the upper end of the other leg of each spring is secured and resiliently supported by said springs; a substantially rectangular web within the supporting frame having sleeves in all of its edges through one of which one end portion of said supporting frame extends; rods in the other sleeves of said web; coiled springs connected to the side portions and the other end portion of said supporting frame and to said rods; and springs connected to the side portions of the seat frame and the supporting frame for stabilizing the supporting frame against side sway.
